RAILWAY TRAFFIC CONTROLLING SYSTEM

Walter W. Wenholz and Carl I. De Long, Rochester, N. Y., assignors to General Railway Signal Company, Rochester, N. Y.

Application November 22, 1929, Serial No. 409,010

20 Claims. (Cl. 246—3)

This invention relates to approach locking means for protecting the operation of power-operated switches, and more specifically to approach locking circuits for power-operated switch machines at the ends of passing sidings on single track railroads equipped with a centralized control or dispatching system.

Where a power-operated switch is operated under manual remote control, for reasons familiar to those skilled in the art, it is important to provide suitable means to prevent operation of the switch in the face of a train approaching at high speed, in order to avoid the possibility that such train will pass over the switch in the wrong position, or in midstroke, or unlocked. Such desired protection may be obtained by what is commonly known as approach locking circuits.

One object of the present invention is to provide a simplified and improved form of such approach locking circuits, particularly applicable to a switch at the end of a passing siding on a single track railroad, which will afford the desired protection and at the same time will not interfere with the operation of the switch by manual control at such times and under such conditions as such operation is safe and proper.

One characteristic feature of the invention is the protection afforded against failure of the approach locking control by the momentary loss of shunting of a track circuit, such as sometimes may happen during movement of a car or short train from one track section to another, or under similar conditions.

Another feature of the invention is an improved form of release control for the approach locking, which is made dependent upon a plurality of track circuits, so as to avoid improper release if the detector track relays should, for any reason, be de-energized while a train is approaching.

Various other characteristic features, functions, and advantages of the invention will be in part apparent, and in part pointed out as the description progresses.

In the accompanying drawings, which illustrate one specific embodiment of the invention, applied to the control of a power-operated switch at one end of a passing siding on a single track railway equipped with a centralized control or dispatching system, Fig. 1 illustrates in a diagrammatic and conventional manner, the relays and circuits constituting the approach locking arrangement of this invention, together with some of the relays associated therewith; and Fig. 2 shows the circuits for the control of the signals governing traffic over the switch equipped with

the approach locking of this invention, together with the control of the switch repeater relay, the various relays, circuits, and other devices illustrated in Figs. 1 and 2, together with others not shown, being employed to constitute a complete system of centralized control for a power-operated switch provided with the approach locking of this invention.

Fig. 1 shows a passing siding PS and portions of the adjacent stretches of the main track. Signals 1—1A, and signals 2—2A govern west-bound and east-bound traffic, respectively, over the switch SW at the east end of the passing siding PS; and signals 3—3A, and 4—4A govern west-bound and east-bound traffic, respectively, over the switch SW—1 at the other end of the passing siding PS. The stretch of main track is divided by insulated joints in the usual way to form track sections, designated 5 to 11 inclusive, each provided with a track battery, or other source of current, designated B, and a track relay, designated 5T, 6T, etc. The track sections 6 and 8 include the switch points and part of the track rails of the siding, up to the fouling point, with suitable cross bonding, in accordance with well-known practice, so as to provide the usual detector track circuits at these switches.

The switch at each end of the passing siding PS is assumed to be operated by a suitable switch machine, preferably of the electrical type, such as shown and described, for example, in the patent to W. K. Howe, No. 1,466,903, dated September 4, 1923. The control circuits for the switch machine at each end of the passing siding, and the approach locking protection therefor, are the same; and for simplicity, the invention has been shown applied to the switch SW at the east end of the passing siding PS, the switch machine for this switch being illustrated conventionally and designated SM.

In the specific embodiment shown, where the invention is applied to a switch of a centralized control or dispatching system, the switch machine SM for operating that switch, and the signals governing traffic over that switch, are controlled in some suitable manner by an operator or dispatcher at a distant point, subject to automatic control by track circuits; and for the purposes of explanation, it is assumed that the switch machine SM, and the signals 1—1A and 2—2A, governing traffic over the associated switch SW, will be controlled by the distant operator by the energization or de-energization of a neutral-polar relay Z over a line circuit.

As shown in Fig. 2, this control relay Z is con-

- 5 nected by line wires 14 and 15, one of which is ordinarily a common wire extending throughout the system, to the contacts 16 and 17 of a control lever LV in the dispatcher's office, the movement of these contacts 16 and 17 from the middle position shown to either extreme position causing energization of the relay Z with direct current of one polarity or the other, as will be obvious from the drawings.
- 10 10 Such energization of the control relay Z causes operation of the switch machine SM to move the switch SW to the normal or reverse position, subject to detector track circuit and approach locking control presently to be described, and 15 also governs the clearing of the signals 1—1A and 2—2A governing traffic over the switch, subject to track circuit control. Also, the energization of this control relay Z, in co-operation with a similar control relay at an adjacent siding 20 end, acts through the agency of the absolute-permissive-block signal circuits, to control the direction of traffic between sidings, dependent upon the sequence in which these control relays are energized, in the manner shown and described in detail in the application of S. N. Wight, Ser. No. 120,423, filed July 3, 1926; but since these specific means for controlling the direction of traffic, and other features characteristic of a complete system of dispatching, are immaterial 25 to the present invention, or essential to an understanding thereof, although preferably used therewith in some form in certain applications of the invention, no attempt has been made to illustrate and describe these features.
- 30 35 For the purposes of explanation of the present invention, it may be assumed that the switch machine SM is governed by the control relay Z in the simple way shown in Fig. 1, the battery 19 providing operating or control current for the switch machine SM over normal and reverse wires 20 and 21, depending upon the polarity of current by which the relay Z is energized providing the approach locking relay LP is energized to close its front contacts 22, these circuits involved being readily traced on the drawings.
- 40 45 The switch machine SM includes suitable point detector contacts PD, such as shown and described, for example, in the patent to C. S. Bushnell, No. 1,517,236, dated November 25, 1924. These point detector contacts PD are shown diagrammatically in Fig. 2 as comprising two contact members 23 and 24, movable from the normal position shown to a reverse position, to open and close circuits through pairs of contacts 25, 26, 27, and 28. These point detector contacts PD also preferably include shunting contacts, comprising movable arms 29 and 30, and co-operating stationary contacts 31 and 32. When the switch points are over and locked in the 50 normal position, contact members 23 and 24 engage the pairs of contact fingers 25 and 26, the shunt contacts 29—31 are closed, and the shunt contacts 30—32 are open, providing a circuit for energizing the switch repeater relay WP with current of one polarity, which may be readily traced from the battery 33 through the contacts 24—26 to the wire 34 leading to the relay WP, and from this relay over wire 35, shunting contacts 29—31 and contacts 23—25 to the other 55 terminal of said battery. When the switch points are over and locked in the reverse position, contact members 23 and 24 engage the pairs of contacts 27 and 28, shunting contacts 30—32 are closed, and shunting contacts 29—31 are open, thereby energizing the relay WP with reverse 60 polarity, over a circuit which may be readily traced by analogy to the one above pointed out. While the switch machine and switch points are in mid-stroke or unlocked, the contact members 23—24 are in an intermediate position, disconnecting the battery 33 from the relay WP, and the shunting contacts 29—31 and 30—32 are both closed, so as to provide a closed circuit for the relay WP, preventing its energization by extraneous current that might be applied to it by 10 crosses or grounds. The switch repeater relay WP is assumed to be of the neutral-polar type, having two neutral armatures 36 and 37, and two polar armatures 38 and 39.
- 15 20 Considering now the control circuits for the signals 1—1A, and 2—2A, and referring to Fig. 2, the signals 1—1A, governing west-bound traffic over the switch SW, are governed jointly by a line relay 1HD and individually by relays 1G and 1AG. Similarly, the signals 2—2A, governing 20 east-bound traffic over the switch SW, are governed jointly by line relay 2HD and individually by relays 2G and 2AG.
- 25 30 The line relay 2HD corresponds to the line relay used in the absolute-permissive-block signal system, and is controlled by the track relays in advance of the signals 2—2A, and between these signals and the next signal in advance, such as 12 (see Fig. 1) governing traffic in the same east-bound direction, and also by the line relay 30 of that advance signal, or a circuit controller operated thereby, so as to provide for the "caution" indication, all in a manner disclosed in the patent to S. N. Wight, No. 1,294,736, dated February 18, 1919.
- 35 40 The other line relay 1HD is similarly controlled by the track circuits in advance of the signals 1—1A, and in accordance with the indication of the advance signal 3; but for purpose of economizing in line wire and relays, this line relay 40 1HD is also provided with special control to adapt it for use in connection with the approach locking.
- 45 50 The complete control circuit for the relay 1HD is shown in Fig. 1, the letter C indicating connections to the usual signal common; and this circuit may be traced as follows:—starting at C, relay 1HD, wire 40, front contact 41 of track relay 7T, wire 42, back contact 43 of relay 3G, corresponding to relay 2G of Fig. 2 and controlling signal 3, wire 44, battery 45, wire 46, and thence either through the front contact 47 of track relay 5T, wire 48 to wire 49, or over wire 50, front contact 51 of the lock relay L—1, and wire 52 to the same wire 49, thence through the front contact 53 of track relay 6T, wires 54 and 55, back contact 56 of relay 3G to C.
- 55 60 In connection with this circuit, it should be understood that the relay L—1 is the lock relay for the switch SW—1, and is controlled in the same way as the lock relay L for the switch SW, as hereinafter explained. It should also be noted that the energization of the relay 3G, through the pole changing action of its contacts 43—56, reverses the polarity of the connection between the battery 45 and the relay 1HD, thereby providing control for causing the signal 1 to indicate "clear" or "caution" depending upon the indication of signal 3.
- 65 70 Referring to Fig. 2, the control circuits for the signals 1—1A and 2—2A are similar, and an explanation of one will suffice for both, it being noted that the signal 2A is arranged to give three indications, while the signal 1A, corresponding to the lower arm of an interlocking signal, merely gives two indications. These signals are assumed 75

to be of the color-light type, although semaphore signals, or signals of any other suitable type may, of course, be used. The circuits for lighting the lamps of these color-light signals are shown in dotted lines terminating at BX and CX; and it will be noted that, when the relay 1G is de-energized, it closes a circuit for lighting the red lamp to give a stop indication, and when energized, permits current to be supplied to the green or yellow lamps, giving clear or caution indications, depending upon the position of the polar armature 57 of the line relay 1HD. Similarly, when the relay 1AG is de-energized, the signal 1A gives a stop indication, and when energized, gives a low speed proceed indication.

The energizing circuit for the relay 1G may be traced (see Fig. 2) from (—), relay 1G, wire 60, front contact 61 of the detector track relay 8T, wire 62, front contact 63 of line relay 1HD, wires 64 and 65, polar contact 38 of the switch repeater relay WP to the right, corresponding with the switch SW normal, wire 66, polar contact 67 of the control relay Z to the right, wire 68, neutral contact 69 of relay Z, wire 70, and neutral contact 37 of relay WP, to (+). The relay 1AG has a similar energizing circuit through the other polar contact 39 of the relay WP, but does not include a front contact of the line relay 1HD.

From these circuits, it can be seen that, when the control relay Z is energized with one polarity, it causes the switch SW to assume its normal position, and when the relay WP indicates that the switch points are actually in that position, the relay 1G may be energized to clear signal 1, subject to the usual block signal control of the line relay 1HD; whereas if the control relay Z is energized with the opposite polarity, and the switch is in the reverse position, the signal 1 indicates stop and the signal 1A is cleared to permit a slow speed movement onto the siding.

It should perhaps be explained that the signal control circuits, as shown in Fig. 2, would apparently provide for the clearing of opposite signals 1 and 2 at the same time, the energizing circuits for the relays 1G and 2G being connected together, but it should be understood that the line relays 1HD and 2HD are suitably controlled, as disclosed in the Wight application, Ser. No. 120,423, above mentioned, so that only one of these line relays is energized at a time, depending upon the sequence of operation of the control levers associated with adjacent ends of the passing sidings.

Considering now the approach locking circuits constituting the present invention, and referring to Fig. 1, the relay LP, which must be energized to permit operation of the switch machine SM, is controlled by the front contact 71 of the detector track relay 8T and the front contact 92 of a lock relay L, so that unless the lock relay L is energized, and the detector track circuit is also unoccupied, the switch machine cannot be operated. The present invention deals more particularly with the control circuits for the lock relay L.

This lock relay L is a stick relay and when once energized by some one of its pick-up circuits, hereinafter pointed out, it is maintained energized by a stick circuit which may be traced (+), front contact 73 of relay L, wires 74, 75 and 76, relay L, wires 77 and 78, back contact 79 of relay 1AG, wire 80, back contact 81 of relay 1G, wire 82, back contact 83 of relay 2AG, wire 84 and back contact 85 of relay 2G to (—).

Thus, once the lock relay L is energized, it is

maintained energized so long as the signals 1—1A, and 2—2A, governing traffic over the switch SW, are held at stop. Under such conditions, it is permissible to operate the switch SW, since any train approaching the switch on the main track 5 will receive a caution indication, and will come to a stop. Whenever one of these signals is cleared by the dispatcher, however, the lock relay L is de-energized, and operation of the switch is prevented, until all of these signals again assume the stop condition to block train movement over the switch.

Since the dispatcher, after clearing one of the signals 1—1A or 2—2A, may at any time thereafter put this signal back to stop, it is necessary 15 to prevent re-energization of the lock relay L in such a case, unless or until it is assured that no train is approaching the switch in obedience to the previous received clear indication, and consequently may not have time to stop before reaching 20 the switch and would encounter the switch in mid-stroke or unlocked.

If there is no such train approaching the switch in either direction, it will be evident that it is proper to permit re-energization of the lock relay 25 L; and for this purpose the line relay 1—HD and an approach relay A are employed in connection with the control of the relay L. The circuit for the approach relay A may be traced from (—), relay A, wire 86, front contact 87 of track relay 30 9T, wire 88, front contact 89 of track relay 10T, wire 90, front contact 91 of track relay 11T, to (+). Thus, if there is a west-bound train in either of the track sections 9 or 10, which may have passed the signal 13 indicating proceed, or 35 if there is a west-bound train in the track section 11, which may be about to pass a signal 13, the approach relay A is de-energized. Similarly, from the control circuit for the line relay 1HD hereinbefore traced, it can be seen that if there 40 is an east-bound train in the section 5 approaching the switch SW under similar conditions, the relay L—1 is de-energized if the signals 4 and 4A are cleared to permit such train to advance, and the relay 1HD is de-energized. In this connection it is of course understood that the relay L—1 is controlled by its associated relays and signals in the same way as is the relay L controlled by its associated relays and signals.

One of the pick-up circuits for the lock relay L, 50 for permitting re-energization thereof, is controlled by a suitable time element device TE, which may be of any suitable construction, but as shown is of the thermal element type, comprising a contact finger 94 of suitable bi-metallic 55 construction, provided with a heating coil 95, and adapted to engage another contact finger 96, after the lapse of a predetermined time, such as (15 to 20) seconds, following the application of current to the heating coil 95. Such a 60 time element device of thermal type is disclosed in the patent of S. N. Wight, Pat. No. 1,856,045, granted April 26, 1932.

Assuming now that the lock relay L has been de-energized by the clearing of one of the signals 65 1, 1A, 2 or 2A, and that the operator has caused the signal cleared to assume again its stop indication, and further assuming that there is no train approaching the switch SW, so that the approach relay A and the line relay 1HD are energized, then 70 there is established a circuit for the heating coil 95 of the time element device TE as follows:— starting at (—), through the back contacts 85, 83, 81, and 79 of the signal control relays 2G, 75 2AG, 1G, and 1AG, with the connecting wires

pointed out, wire 97, back contact 98 of relay L, wire 99, coil 95, wire 100, front contact 101 of a detector track circuit repeater relay 8TP, wire 102, front contact 103 of relay A, wires 104 and 105, and front contact 106 of relay 1HD to (+).

Current flowing in this circuit heats the coil 95, and after the lapse of a suitable time interval, which may be assumed to be approximately (15 to 20) seconds, the contacts 94—96 of the time element device TE are closed, whereupon a pick-up circuit for the relay L is established through the back contacts of signal control relays 2G, 2AG, 1G and 1AG, through the relay L, wires 16 and 107, contacts 94—96 of the time element device TE, and through the front contacts 101, 103 and 106 of the relays 8TP, A and 1HD.

The time interval provided by the time element device TE, in the embodiment of the invention shown, performs two different functions. It will be noted that, even if the relays 8TP, A and 1HD should be energized at the time the operator caused a clear signal to assume the stop position, the relay L is not at once re-energized, but only after the lapse of the time interval provided by the device TE. This assures that any east-bound train on the siding PS, which is ordinarily not equipped with track circuits, will have time to stop or advance into the detector track section 8, whereupon operation of the switch is directly prevented by de-energization of the relay LP, after the signal 2A is put to stop by the operator, if such train should happen to be in such position as to be making a low speed movement over the switch in obedience to a proceed indication of the signal 2A. In other words, the time element device TE provides time release for the approach locking to take care of the train movement off of the siding.

Another function of the time element device TE is to prevent energization of the lock relay L, in the event that either the approach relay A or the line relay 1HD, while de-energized by an approaching train, should be momentarily picked up, due to the temporary loss of shunting of the track circuits, for any cause, as for example, due to the picking up of one track relay before the dropping of adjacent track relay by a short high-speed train or car. In other words, if an approaching car or train, which should maintain the lock relay L de-energized, should momentarily fail to keep the relays A, 1HD de-energized, on account of the operating limitations of track circuits, the time element device TE affords the desired protection by preventing immediate response of the relay L. In this connection, it should be understood that the time interval for this purpose may ordinarily be much less than the time interval required to protect a train movement off of the siding; so that if desired, separate time element devices, with different time intervals of operation, may be employed to perform these two different functions; but it is preferred to employ a single time element device, as shown, since a reasonable delay in the re-energization of the lock relay L does not interfere with practicable operation.

Considering now the case of normal train movements, where a signal has been cleared by the operator and is left in that condition until a train has passed the switch and then returned to the stop position, the lock relay L is energized by another pick-up circuit which may be traced through the back contacts of the signal control relays 2G, etc., through the relay L, wires 76, 75, 74, 110, through the back contact 101 of the de-

tector track circuit repeater relay 8TP, wire 102, back contact 103 of approach relay A, wire 111, another back contact 112 of relay 8TP, wires 120 and 113 (assuming switch normal), and back contact 106 of line relay 1HD, to (+). If the switch is in the reverse position, this pick-up circuit is over wires 120 and 114, polar contact 115 of the switch repeater relay WP in reverse position, wires 116 and 105, and front contact 106 of the line relay 1HD. There is still another pick-up circuit for relay L, which includes the back contact 101 of relay 8TP and wire 110, but this circuit is more fully traced hereinafter.

To appreciate the significance of the control of this pick up circuit just traced, and the conditions under which it is established, assume a west-bound train movement, with the switch SW in the normal position. This west-bound train de-energizes approach relay A, closing its back contact 103, and when this train enters the detector track circuit 8, it shunts the detector track relay 8T and in turn drops the repeater relay 8TP, closing its back contact 112. As the train further advances and enters the track section 7, the line relay 1HD is de-energized, wherupon the complete pick-up circuit for the relay L is established.

If the switch SW is in the reverse position, the west-bound train would pass onto the siding, and would not enter the track section 7, so that the pick-up circuit for the relay L in this case is through the front contact 106 of the relay 1HD, and includes the polar contact 115 of the relay WP.

An east-bound train on the main track establishes the pick-up circuit for the relay L, when it enters the track section 9, in the same way as a west-bound train, this because with relays 8TP and 1HD deenergized the relay A must also be deenergized to complete the pick-up circuit for relay L. An east-bound train from the siding picks up the relay L through the back contact 101 of the relay 8TP and the front contacts of the relays A and 1HD, as soon as this train enters the detector track section 8, it being noted that such release will occur only if there is no other train within the approach locking limits in both directions, but will occur if there is a train in each of these approach sections at the same time, that is, with relays 8TP, A and 1HD all down, and this is a safe condition for reasons given below.

It can be seen that this pick-up circuit for the relay L with an east-bound train on the main track is dependent upon the shunting of two or more track relays. This is done in order to avoid a possible unsafe condition by improper release of the approach locking, in the event that one track relay, such as the detector track relay 8T, should for some reason be shunted while there is a train within only one of the approach locking limits. For example, if the release of the approach locking were dependent only upon the shunting of the detector track relay 8T, it might happen that, while a train was approaching, this track relay would be shunted for some reason, as for instance, by a maintainer working on the system; and the operator, believing that such accidental shunting of the detector track relay meant the arrival of the expected train, might change his control lever to operate the switch in the face of the approaching train. After a little consideration, it will be appreciated that such an unsafe condition is obviated by making the re-energization of the lock relay L dependent upon simul-

taneous shunting of a plurality of different track circuits.

In the case of a long train as above assumed, the track relays 7T and 8T and 9T are simultaneously shunted to provide the pick-up circuit for the relay L, following change of the cleared signal to its stop condition upon entrance of the train into the track section 8. In the case of a single car, or a train shorter than the length of the detector track section, the relay L is picked up through the back contact 101 of the detector track circuit repeater relay 8TP and the front contacts 103 and 106 of the relays A and 1HD. If the train should happen to be of such length and travelling at such a speed, that the relay 1HD is dropping at the same instant the relay A is picking up, so that these relays A and 1HD are not both either picked up or dropped at the same time, long enough to energize the relay L, then the desired release of the approach locking will not take place, but this combination of train length and speed is very remote and so rarely occurs in practice, it is found, that there is no practical limitation imposed upon the operation.

In connection with this feature of re-energizing the relay L by a plurality of track circuits, it should perhaps be explained that, with a train on the track section 7 de-energizing the relay 1HD, and a west-bound train approaching the switch SW and de-energizing the approach relay A, dropping of the detector track circuit repeater relay 8TP under these conditions would energize the relay L, and might appear to cause an unsafe condition; but in this case, the train on the track section 7 holds at stop the signal 1, and the west-bound train in question would receive at the signal 13 a caution indication, with this signal 1 at stop or with the signal 1A cleared and consequently would be approaching the switch prepared to stop. Consequently, while in this particular case the relay L would be energized by accidental or improper shunting of the detector track relay 8T, this would take place under such conditions of train position and train movement that no train would be approaching at high speed.

To provide for an emergency release of the approach locking, a contact 121 is preferably provided to close a circuit from (+), over wires 117 and 16, to the relay L, and thence through the back contacts of the signal control relays 2G, etc., the same as if a train had passed the detector track section, or a time interval had elapsed. This contact 121 may be a push-button or hand switch, suitably housed and protected, or a contact on the dual control selector, which may be applied to the switch, in accordance with the disclosure of the patent of W. K. Howe, Pat. No. 1,852,573, granted April 5, 1932. It should be understood that this contact 121 is only closed by a trainman at the switch, under the instruction and supervision of the operator, who is in telephone communication with the siding in the usual way.

From the foregoing, it can be seen that there is provided by this invention a relatively simple and efficient arrangement of circuits, relays and a time element device for affording the desired approach locking protection for a power operated switch, without interfering with the operator's control of the switch at all times when safety permits, and at the same time affording a high degree of protection against improper operation due to unexpected or improper shunting of track relays.

The particular combination and arrangement

of circuits and devices shown and described is merely typical or illustrative of one embodiment of the invention, and its application to one type of signaling system involving a power-operated switch; and it should be understood that the specific embodiment of the invention disclosed is susceptible of various modifications, adaptations, and additions, without departing from the invention.

What we claim is:—

1. In a system of approach locking for power-operated switches, signals governing traffic over the switch, a stick relay acting when de-energized to prevent operation of said switch, a time element device having a circuit controller closed after the lapse of a predetermined time, contacts opened by a train approaching the switch, and a pick-up circuit for said relay including said circuit controller and said contacts in series, said time element device being set into operation only if said signals indicate stop and said train governed contacts are closed.

2. In a system of approach locking, a stick lock relay, a detector track relay, approach relays respectively de-energized by a train approaching the switch from opposite directions, and a pick-up circuit for said stick relay including in series back contacts of said detector track relay and of said approach relays.

3. A system of approach locking comprising, a lock relay, a detector track relay, two contacts separately closed by a train on opposite sides of the track section in which said detector track relay is located, and an energizing circuit for said lock relay including in series said two contacts and a back contact of said detector track relay.

4. In a system for protecting the operation of a power-operated track switch, the combination with a lock relay governing the operation of the switch, signals governing traffic over the switch, three adjacent track circuits associated with said track switch, a stick circuit for said relay closed when said signals indicate stop, and a pick-up circuit for said relay closed after a predetermined time only if said signals indicate stop and three adjacent track circuits are simultaneously unshunted.

5. In a system of approach locking of the type described, the combination with a power-operated switch and manual control means therefor, of a lock relay, a detector track relay associated with said switch, two approach relays one if de-energized manifesting the approach of a train from one direction and the other if deenergized manifesting the approach from the other direction, a circuit for said lock relay including front contacts of said detector track relay and front contacts of both of said approach relays in series, and another circuit for said lock relay including back contacts of said detector track relay and back contacts of both of said approach relays in series.

6. In a system of approach locking of the type described, the combination with a power-operated switch and manual control means for the switch, of a lock relay, a detector track relay associated with said switch, two approach relays one if deenergized manifesting the approach of a train from one direction and the other if deenergized manifesting the approach from the other direction, and means for energizing said lock relay requiring said detector and approach relays to either all assume their energized position or all assume their deenergized position.

7. In a system of approach locking of the type

described; the combination with a power-operated switch and a lock relay governing the operation of said switch; an approach relay means therefor deenergized by a train approaching said switch; a signal associated with said switch; and means jointly responsive to the lapse of time, the stop condition of said signal and the energized condition of said approach relay for governing said lock relay.

10. In a system of approach locking; a stick lock relay; a detector track relay; approach relays respectively deenergized by a train approaching the switch from opposite directions; a signal associated with said switch; and a pick-up circuit for said stick relay including in series a contact closed when said signal is at stop, a back contact of said detector track relay and back contacts of said approach relays.

11. In a system for protecting the operation of a power-operated track switch; the combination with a stick lock relay governing the operation of such switch; signals governing traffic over such switch; three adjacent track circuits associated with said switch and said signals; a stick circuit for said relay closed when said signals indicate stop; and a pick-up circuit for said relay closed by said signals indicating stop and three adjacent track circuits simultaneously occupied.

12. In a system for protecting the operation of a power-operated track switch, the combination with a lock relay governing the operation of such switch, signals governing traffic over such switch, three adjacent track circuits associated with said switch and said signals; a stick circuit for said relay closed when said signals indicate stop; a pick-up circuit for said relay closed after a time only if said signals indicate stop and the middle one of said three adjacent track circuits is unoccupied and the other two track circuits are also unoccupied, and another pick-up circuit for said relay closed if said signals indicate stop; and the middle one of said three adjacent track circuits is occupied and the other two track circuits are unoccupied, said another pick-up circuit acting without a time delay.

13. In a system for protecting the operation of a power-operated track switch, the combination with a lock relay governing the operation of such switch, signals governing traffic over such switch, three adjacent track circuits associated with said switch and said signals; a stick circuit for said relay closed when said signals indicate stop; and a pick-up circuit for said relay closed if said signals indicate stop and the middle one of said three adjacent track circuits is occupied and the other two of said adjacent track circuits are unoccupied.

14. In a system for protecting the operation of power-operated switches; the combination with a lock relay governing the operation of such switch; a signal governing traffic over such switch; a detector track section; an approach track section for said signal; a stick circuit for said relay closed when said signals indicate stop; and a pick-up circuit for said relay closed if said signals indicate stop, said power-operated switch assumes the reverse position and said detector track section associated with said switch and said approach track section are both occupied.

15. In combination, a main section of railway track containing a switch, an approach section, a track circuit including a track relay for each section, a signal for governing traffic into said main section, an approach locking relay for the control of said switch, a slow-acting device having an energizing winding and a normally open contact,

means for energizing the winding of said slow-acting device when said signal indicates stop if and only if said approach locking relay is de-energized and the track relay for said main section is energized, and means for controlling said approach locking relay by said track relays and by said contact of said slow-acting device.

16. In combination, a main section of railway track containing a switch, an approach section, a track circuit including a track relay for each section, a signal for governing traffic into said main section, an approach locking relay for the control of said switch, a slow-acting device having an energizing winding and a normally open contact, means for energizing the winding of said slow-acting device when said signal indicates stop if and only if said approach locking relay is de-energized and the track relay for said main section is energized, and means for controlling said approach locking relay by said track relays by the contact of said slow-acting device and by a contact reflecting the indicating condition of said signal.

17. In combination, a main section of railway track containing a switch, a track circuit includ- 25 ing a track relay for said section, a signal for governing traffic into said main section, an approach locking relay for the control of said switch, a slow-acting device having an energizing winding and a normally open contact, means for en- 30 ergizing the winding of said slow-acting device when said signal indicates stop if and only if said approach locking relay is deenergized and the track relay for said main section is energized, and an energizing circuit for said approach lock- 35 ing relay including a contact closed when said slow acting device is energized and a contact closed when said signal is at stop.

18. In combination; a power operated track switch; approach track sections on opposite ends 40 of said track switch; a stick lock relay for when deenergized preventing power operation of said track switch; signals for governing the movement of traffic over said track switch; and two pick-up circuits for said stick relay, one of which 45 is closed only if all said signals are at stop and both of said approach sections are occupied, and the other of which is closed only if all of said signals are at stop and both of said approach sections are unoccupied. 50

19. In combination; a power operated track switch; approach track sections on opposite ends of said track switch; a stick lock relay for when deenergized preventing power operation of said track switch; signals for governing the movement 55 of traffic over said track switch; two pick-up circuits for said stick relay, one of which is closed only if all said signals are at stop and both of said approach sections are occupied, and the other of which is closed only if all of said signals are at stop and both of said approach sections are unoccupied; and a stick circuit for said stick relay closed only if all of said signals are at stop.

20. In combination; a power operated track switch; approach track sections on opposite ends 60 of said track switch; a stick lock relay for when deenergized preventing power operation of said track switch; signals for governing the movement of traffic over said track switch; two pick-up circuits for said stick relay, one of which is closed only if all said signals are at stop and both of said approach sections are occupied, and the other of which is closed only if all of said signals are at stop and both of said approach sections are unoccupied; another pick-up circuit for said stick 75

relay closed only if a detector track circuit associated with said track switch is occupied and said signals are at stop; and a stick circuit for said stick relay closed only if all of said signals are at stop.

- 5 19. In combination; a power operated track switch; approach track sections on opposite ends of said track switch; a stick lock relay for when deenergized preventing power operation of said track switch; signals for governing the movement of traffic over said track switch; and two pick-up circuits for said stick relay, one of which is closed only if all said signals are at stop and both of said approach sections are occupied, and the other of which is closed only if all of said signals are at stop and both of said approach sections are unoccupied; and another pick-up circuit for said stick relay closed only if one of said approach sections is occupied and the other is unoccupied providing said track switch assumes the reverse position.
- 10 15 20

20. In combination; a power operated track switch; approach track sections on opposite ends of said track switch; a stick lock relay for when deenergized preventing power operation of said track switch; signals for governing the movement of traffic over said track switch; two pick-up circuits for said stick relay, one of which is closed only if all said signals are at stop and both of said approach sections are occupied, and the other of which is closed only if all of said signals are at stop and both of said approach sections are unoccupied; another pick-up circuit for said stick relay closed only if one of said approach sections is occupied and the other is unoccupied providing said track switch assumes the reverse position, and a stick circuit for said stick relay closed only if all of said signals are at stop.
